COKE OVEN DOORS

Adolph A. Backoff, deceased, late of Gary, Ind., by
 Sidney Krieger, administrator, Gary, Ind., as
 signor to Alois W. Graf

Application May 8, 1946, Serial No. 668,155

5 Claims. (Cl. 202—248)

1

This invention relates to an improvement in coke oven doors.

The doors used at present on coke ovens must be lifted entirely off the door frame and carried away by a machine called a door extractor. Some doors are made gas tight by luting, that is, packing clay around the cracks of the door. Other doors are self-sealing, that is they have a knife edge which bears on the door frame under spring pressure. When it is desired to open the coke oven door the extractor unlatches the door, lifts it off its support, and then carries it away. Since the doors are heavy, it requires a heavy extracting machine to handle them. On the pusher side of the oven the extractor is included as part of the pusher, while on the discharge side it is an independent machine. To make even minor repairs it is necessary to remove the door and install another door in its place. These doors are unsatisfactory because of the difficulties of maintenance and because of the heavy and expensive machinery necessary to open and close them.

It is an object of this invention to provide an improved coke oven door which need not be removed when the coke is pushed out of the oven.

It is a further object of this invention to provide an improved coke oven door structure which is economical to operate and maintain.

It is another object of that invention to provide a rotating door mounted on pivots and shaped so that it will allow a clear passage of the coke and ram when swung to an open position.

Another object of this invention is to provide such a door which can be swung through an angle of 180° to provide for inspection and repair of its refractory face.

These and other objects will be more apparent after referring to the following specification and attached drawings, in which:

Figure 1 is a front elevation of the door in place in closed position;

Figure 2 is a sectional view taken on the line 2—2 of Figure 1;

Figure 3 is a top plan view taken on the line 3—3 of Figure 2;

Figure 4 is a sectional view taken on the line 4—4 of Figure 2;

Figure 5 is a sectional view taken on the line 5—5 of Figure 2;

Figure 6 is a view similar to Figure 5 but showing the door in open position;

Figure 7 is a sectional view taken on the line 7—7 of Figure 2;

2

Figure 8 is a sectional view taken on the line 8—8 of Figure 2;

Figure 9 is an enlarged horizontal sectional view of the door frame;

Figure 10 is a front elevation of the top portion of the door frame;

Figure 11 is a sectional view taken on the line 11—11 of Figure 9; and

Figure 12 is a plan view of a coke oven showing a door in various positions.

Referring more particularly to the drawings, the coke oven has an entrance 2 into the coking chamber. It will be understood that the coking chamber is of substantially the same cross sectional shape throughout its length and that the doors at the pusher end, and the coke end will be of the same type although the width of the chamber at the pusher end is slightly less than that at the coke end. The refractory brick work 4 of the oven has an embedded metallic door frame 6. On each side of the opening 2 are the conventional vertical buckstays 8. As best shown in Figures 9, 10 and 11, the door frame has a cylindrical concave inner surface 10 at each side and a flat upper surface 12. The door frame is fastened to the buckstays 8 in any suitable manner. As shown, a bolt 14 passes through a plate 15 and is fastened to the buckstays 8. The plate 15 bears against the frame 6 and holds it in position. The door body 16 has a cylindrically shaped convex inner surface 18 which is connected by a relatively straight outer surface 20. The door body is made of a reinforcing metal skeleton 22 which may be a single casting or may be fabricated from a plurality of parts riveted or welded together. The flanges 24 of the reinforcing skeleton 22 are cylindrically shaped and have substantially the same radius as the cylindrical surfaces 10 of the door seat. The skeleton 22 is filled with a refractory material 26 which is set back of the flanges 24 to provide a certain clearance 28. A sealing groove 30 is cut in the door body flanges 24 and extends entirely around the door body. The groove 30 has an inlet 32 and an outlet 34. A sealing solution with a consistency more or less that of a putty is pumped through the inlet 32 into and around the groove 30 until it emerges from the outlet 34. A dam 36 is provided in the groove 30 to prevent the sealing solution from shortcircuiting from inlet 32 to outlet 34. Connected to the door skeleton 22 is a bottom trunnion 38 which is supported by self-aligning ball bearings 40. The bearings 40 rest on a base plate 42 which is rigidly connected to the coke oven in any suitable man-

ner. Beneath the plate 42 is a cam 44 which is fastened and keyed to the trunnion 38 by a bolt 46 and a key 47. Adjacent the cam 44 is a plate 48 which provides a surface against which the cam 44 bears. Extending outwardly below the plate 48 is a bracket 50 having a bore 52 threaded on its outer end for receiving a spring loaded screw 54. A cam follower 56 is provided in the bore 52 and a spring 58 presses it against the cam 44. Connected to the top of skeleton 22 is a top trunnion bracket 60. A trunnion pin 62 is tightly keyed to the top trunnion bracket 60 by means of a key 63 and extends upwardly through a bushing 64 which has a square outer surface. A bevel gear 66 and a cam 68 are keyed to the top of the pin 62 by means of a key 69. Meshing with the bevel gear 66 is a bevel pinion gear 70 which is mounted on a pin 72 for movement therewith. The pin 72 is carried in bearings 74 of a bevel gear housing 76 and has a square outer end 78 which is received in the socket 80 of the power driven wrench. On the pusher side of the coke oven the wrench may be mounted on the pusher while on the coke side the wrench is separately mounted. The square bushing 64 fits in a slotted hole 82 of a bracket 84 which is attached to the coke oven in any suitable manner and has a permissible movement 86 which equals the throw of the cam 68. Similar clearance 88 is provided in the plate 42 to permit clearance between the door body and door frame during rotation of the door frame. The cam 68 also is provided with a bearing plate 48, a bracket 50 having a bore 52, and a spring biassed cam follower 56, all arranged around the cam 68 in the same manner as around the cam 44 as described above. A pocket 90 is provided in the outer surface of the door for picking up and handling the doors when they are being replaced.

When it is desired to close the doors for coking, the socket 80 of the wrench is placed over the square head 78 of shaft 72. The wrench is then rotated which rotates pin 62 through bevel gears 66 and 70. After the door is rotated through an angle of about 90° from the open position shown in Figure 6 to the closed position shown in Figure 5, the rotation is stopped and the wrench removed. During this rotation the cams 44 and 68, respectively, bear against their respective cam followers 56 to slide the door through the distance 86 and 88, thus forcing it against its seat. The sealing solution is then pumped into the groove 30 through the inlet 32. This closed position of the door is shown in full lines in Figure 12 and is indicated as position A. When it is desired to open the door to discharge the coke from the oven, the door is rotated in like manner through an angle of 90° to either position B as shown in Figure 12. During this movement the cams 44 and 68 bear on the surfaces of plates 48 to break the seal. The distance between the door pivot bolts 46 and 62 and the outer door surface 20 is equal to approximately one-half of the width of the opening 2 so that when the door is rotated through an angle of about 90° from the closed position, the entire door is back of the side walls of the coke oven as shown in Figure 12. This permits the pusher ram to push the coke from the oven without interference. When it is desired to open the doors for inspection or for repairing the inner surface thereof, they are rotated 180° from the closed position. This throws the surface 18 to the outside as shown in position C in Figure 12 so that the refractory 26 can be repaired.

5 While one embodiment of the invention has been shown and described, it will be apparent that other adaptations and modifications may be made without departing from the scope of the following claims.

6 What is claimed is:

1. In a coke oven the combination comprising a cylindrical door seat, a door body having a cylindrically shaped inner surface, the cylindrical door seat and cylindrical inner surface having substantially the same radius, a grove in said door for providing a seal between said surface and said seat, top and bottom pins spaced outwardly from the outer surface of said door for pivotally supporting said door body, means for permitting movement of the pins toward and away from the door seat, a cam mounted on each of the pins, an inner surface against which the cam bears to break the seal when the door is opened, and an outer surface against which the cam bears to hold the door body against the seat when the door is closed.

2. A coke oven door comprising a cylindrical concave door seat, a door body having a cylindrically shaped convex inner surface connected by a relatively straight outer surface, the cylindrical door seat and cylindrical inner surface having substantially the same radius, a groove in said door for receiving sealing material to produce a seal between said seat and said door, top and bottom pins spaced outwardly from said outer surface for pivotally supporting said door body, means for linearly moving the pins toward and away from the door seat, including a cam mounted on each of the pins, an inner surface against which the cam bears to break the seal when the door is opened, a spring biassed outer surface against which the cam bears to hold the door body against the seat when the door is closed, and means for rotating said door.

3. A coke oven door comprising a cylindrical door seat, a door body having a cylindrically shaped inner surface connected by a relatively straight outer surface, the cylindrical door seat and cylindrical inner surface having substantially the same radius, a groove in the inner surface of said door extending adjacent its edges for receiving sealing material to produce a seal between said door and said seat, conduits interconnecting said groove with the outer surface of said door, top and bottom pins spaced outwardly from said outer surface for pivotally supporting said door body, means for moving the pins toward and away from the door seat, including a cam mounted on each of the pins, an inner surface against which the cam bears to break the seal when the door is opened, and an outer surface against which the cam bears to hold the door body against the seat when the door is closed.

4. In a coke oven, the combination comprising a door seat having vertical sides in the form of sections of a cylinder, a door body having a cylindrically shaped inner surface and a generally flat outer surface, said inner surface and said vertical sides of said door seat having substantially identical radii, top and bottom pivot supports for said door spaced outwardly from said flat outer surface, a sealing groove provided in the inner surface of said door body adjacent the edges thereof, conduits interconnecting said groove with the outer surface of said door whereby sealing material may be supplied to said groove, a cam mounted adjacent each of said pivot supports, means for rotating said cams and 70 said door body, inner surfaces against which said

cams bear to break the door seal, and resiliently biased outer surfaces against which said cams bear to hold the door body against said door seat.

5. In a coke oven the combination comprising a door seat having concave surfaces, a door body having inner convex surfaces generally complementary to the concave surfaces of said seat, said door body having a generally flat outer surface, supporting means located at opposite ends of said door body, a pivotal connection formed in each support for rotating said body about an axis displaced from said outer surface, a cam connected to each pivotal connection for producing a linear horizontal movement of said connections and said body, and means for rotating said cams and said body through an arc of 90° whereby the flat outer surface of said door will be parallel to the vertical edge of said door seat and said door seat will be unobstructed.
